UNITED STATES PATENT OFFICE.

SQUIER WILDER, OF HUNTINGDON, TENNESSEE.

CULTIVATOR.

1,131,303.

Specification of Letters Patent. Patented Mar. 9, 1915.

Application filed September 19, 1913. Serial No. 790,741.

To all whom it may concern:

Be it known that I, SQUIER WILDER, a citizen of the United States, residing at Huntingdon, in the county of Carroll and State of Tennessee, have invented a new and useful Cultivator, of which the following is a specification.

The device forming the subject matter of this application is a cultivator of the cylinder type.

10 The implement is adapted to be employed for cultivating and pulverizing soil about different sorts of crops, such as corn, cotton, potatoes and the like, and, in general, under all conditions in which a machine of the character hereinafter described may be employed to advantage.

20 One object of the invention is to provide means for moving the cylinder in a direction parallel to its axis, so that the cylinder may work at a greater or less distance from the standing row.

The invention aims to provide novel means for rotating the cylinder.

25 It is within the province of the invention to improve generally and to enhance the utility of devices of that type to which the present invention appertains.

With the above and other objects in view 30 which will appear as the description proceeds, the invention resides in the combination and arrangement of parts and in the details of construction hereinafter described and claimed, it being understood that 35 changes in the precise embodiment of the invention herein disclosed can be made within the scope of what is claimed without departing from the spirit of the invention.

In the accompanying drawings:—Figure 40 1 shows in front elevation, a cultivator constructed in accordance with the present invention, parts being broken away; Fig. 2 is a top plan of the cultivator, portions being broken away and sectioned; Fig. 3 is a 45 cross section on the line 3—3 of Fig. 2, portions being broken away; Fig. 4 is a perspective of the cylinder together with a portion of its supporting shaft; Fig. 5 is a 50 sectional detail illustrating a portion of the clutch mechanism.

In carrying out the invention and referring particularly to Figs. 1 and 2 for a general understanding of the structure, there is provided a wheel mounted main frame including a tongue 1 supporting a seat 2. Secured as indicated at 3 to the tongue 1 is an

arched axle 4, the horizontally disposed, outwardly projecting ends of which are denoted by the numeral 5. The main frame of the machine includes a rear cross bar 6 held in place upon the tongue 1 by means of a clip 7 and bolts 8. Adjacent its ends and in its upper edge the rear cross bar 6 is equipped with notches 9. A front cross bar 10, somewhat shorter than the rear cross bar 6, forms a portion of the main frame and is held in place upon the tongue 1 by means of a clip 11 and bolts 12. The front cross bar 10 is sustained by means of rearwardly extended converging braces 14, secured as indicated at 15 to the tongue 1, the forward ends of the braces 14 being connected with certain of the bolts 12.

The invention includes two duplicate mechanisms, located upon opposite sides of 75 the machine, and but one of these mechanisms will be set forth in detail.

Journaled for rotation upon one of the ends 5 of the arched axle 4 is a drive wheel 16 which, as best shown in Fig. 3 comprises 80 a rim 17, spokes 18 and traction teeth 19 projecting from the rim. The spokes 18 of the drive wheel 16 support a shoulder 20 to which is secured a sprocket wheel 21. Mounted to swing upon the end 5 of the axle 85 4 is a frame which is a composite structure, the frame comprising a pair of angular supports 22, the rear ends of which receive the part 5 of the axle 4, as Fig. 3 will most clearly show. Adjacent their apices, the 90 angular supports 22 are equipped with vertically adjustable bearings 23 controlled by screws 24 or in any other suitable manner.

Journaled in the bearings 23 is a shaft 25. Mounted to rotate upon the shaft 25 and 95 held in place against transverse movement by pins 29 as shown in Fig. 5, is a sprocket wheel 26. About the sprocket wheel 26 and the sprocket wheel 21 is trained a sprocket chain 27. The hub of the sprocket wheel 26 is indicated at 28 and is equipped at its inner side with a clutch 30. Mounted to move upon the shaft 25 longitudinally of the same 100 is a clutch 31. The teeth of the clutch 31 are adapted to coöperate with the teeth of the clutch 30 and between certain teeth of the clutch 31, one pin 29 on the shaft 25 is received. By moving the clutch 31 longitudinally of the shaft 25, the sprocket wheel 26 may be coupled up with the shaft 25 so 110 that when the drive wheel 16 is rotated, motion will be transmitted through the

sprocket wheel 21, the sprocket chain 27 and the sprocket wheel 26 to the shaft 25, to the end that rotation may be imparted to the pulverizing cylinder to be described herein-after. In the periphery of the clutch 31 there is formed a groove 32. Coöperating with the groove 32 in the clutch 31 is a rear-wardly extended lever 35 mounted loosely on a fulcrum pin 34 carried by a cross bar 33 5 extended between the angular supports 22. This lever 35 is adapted to be moved in the direction of the arrow A in Fig. 1 and may be engaged with the notches 9 in the rear cross bar 6, the function of the lever 35 being to shift the clutch 31 into and out of engagement with the clutch 30 on the sprocket wheel 26.

Secured to the outer end of the shaft 25 is a sprocket wheel 36 receiving a sprocket 20 chain 37 trained around a sprocket wheel 38 secured to a shaft 39 journaled in a bearing 40 which is secured to the lower, forward ends of the angular supports 22. The inner end of the shaft 39 is squared as shown at 25 41 and mounted on the squared portion 41 of the shaft, adjacent the inner extremity thereof is a pin 42 which is shown most clearly in Fig. 1.

A pulverizing cylinder, shown in Fig. 4 30 is provided and this cylinder is mounted upon the squared portion 41 of the shaft 39 to slide thereon in the direction of the axis of the shaft but to rotate along with the shaft. The pulverizing cylinder may be 35 variously constructed but in the present instance it is shown as comprising a pair of disks 43 and 44 and an inner band 45, spaced from the disk 44. The disks 43 and 44 and the band 45 are peripherally connected by a 40 plurality of slats 46 which define acute angles with the axis of the shaft 39. The slats 46 carry pulverizing teeth 47 which may be held in place in any desired manner.

It will now be understood that from the 45 shaft 25 rotation is imparted to the shaft 39 and the pulverizing cylinder 43-44-45 through the medium of the sprocket wheel 36, the sprocket chain 37 and the sprocket wheel 38.

50 A means is provided for moving the pulverizing cylinder 43-44-45 longitudinally of the squared portion 41 of the shaft 39 and with this end in view, a spool 48 (shown in Figs. 1 and 2 but omitted in Fig. 4) is attached to the disk 43, the spool 48 receiving the forked end of a lever 49 which is fulcrumed as shown at 50 upon the end portion 5 of the axle 4 to swing in the direction of the arrow A in Fig. 1. By manipulating the lever 49, the cylinder 43-44-45 may be adjusted longitudinally of the shaft 39, for the purpose hereinbefore set forth.

In order that the pulverizing cylinder 43-44-45 may be raised and lowered along 55 with the frame comprising the angular sup-

ports 22 and the connections 33 and 40 there-between, a lever 51 is fulcrumed at 52 upon the end of the front cross bar 10, there being a link 53 which connects the forward end of the lever 51 with one of the angular supports 22, as shown in Figs. 1 and 3. A locking device 54 of any desired construction may be mounted upon the cross bar 6 for holding the lever 51 in adjusted positions.

The operation of the structure has been set out step by step hereinbefore but briefly considered is as follows:—The pulverizing cylinder 43-44-45 is rotated by a gear train comprising the drive wheel 16, the sprocket wheel 21, the sprocket chain 27, the sprocket wheel 36, the sprocket chain 37, the sprocket wheel 38 and the shaft 39. The sprocket wheel 26 is coupled up operatively with the shaft 25 by manipulating the lever 35. The pulverizing cylinder 43-44-45 is moved longitudinally of the shaft 39 through the medium of the lever 49. The pulverizing cylinder 43-44-45 may be raised and lowered by tilting the frame comprising the angular supports 22 through the medium of the link 53 and the lever 51.

Although the implement has been shown as comprising duplicate mechanisms of the sort hereinbefore described, it is obvious, 95 notably from Figs. 1 and 2, that one pulverizing cylinder may be employed as advantageously as two.

Having thus described the invention, what is claimed is:—

1. In a cultivator of the class described, a main frame including an axle; a ground wheel on the axle; an auxiliary frame pivoted upon the axle and having angularly related portions extended downwardly and forwardly with respect to the axle; a sprocket wheel mounted to move with the ground wheel; a primary sprocket wheel journaled on the lower end of the downwardly extended portion of the auxiliary frame; a secondary sprocket wheel journaled for rotation at the angle between said frame portions, the sprocket wheels on the auxiliary frame acting as weights for depressing the forward end of the auxiliary frame; a soil engaging element operatively connected with the primary sprocket wheel; a sprocket chain forming an operative connection between the primary and secondary sprocket wheels; a sprocket chain forming an operative connection between the secondary sprocket wheel and the sprocket wheel which is mounted to move with the ground wheel; and means for raising and lowering the forward end of the auxiliary frame with respect to the axle. 115

2. In a cultivator of the class described, a main frame including an axle; a ground wheel on the axle; an auxiliary frame pivoted upon the axle and having angularly related portions extended forwardly and down- 130

wardly with respect to the axle; a sprocket wheel mounted to move with the ground wheel; a primary sprocket wheel journaled on the lower end of the downwardly extended portion of the auxiliary frame; a larger, secondary sprocket wheel journaled for rotation at the angle between said frame portions, the sprocket wheels on the auxiliary frame acting as weights for depressing the 10 forward end of the auxiliary frame; a soil engaging element operatively connected with the primary sprocket wheel; a sprocket chain forming an operative connection between the primary and secondary sprocket wheels; a sprocket chain forming an operative connection between the secondary sprocket wheel and the sprocket wheel which is mounted to move with the ground wheel; a lever fulcrumed intermediate its ends on the main frame; and a substantially vertical 20 link forming an operative connection between one end of the lever and the forward portion of the auxiliary frame.

SQUIER WILDER.
